Primary Examiner—Robert M Spear*Assistant Examiner*—Carla Jobe Wright(74) *Attorney, Agent, or Firm*—Steven M. Reiss(57) **CLAIM**

The ornamental design for an electronic device, as shown and described.

DESCRIPTION

FIG. 1 is a perspective view of an electronic device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of unclaimed portions of the electronic device is directed to environment and forms no part of the claimed design.
